ACETYLENE GENERATOR

Maurice P. De Motte, Indianapolis, Ind., assignor
to Oxweld Acetylene Company, a corporation
of West Virginia

Application January 11, 1930, Serial No. 420,147

22 Claims. (Cl. 48—22)

This invention pertains to acetylene generators and more specifically to means for manually controlling the gas pressure of such a generator from the outside thereof, and to means for automatically maintaining a substantially uniform pressure in such a generator during the life of a charge of carbide.

One of the objects of this invention is to provide an acetylene generator of the ebb-and-flow, 10 water-feed type, with means for manually controlling the gas pressure thereof from the outside of the generator, so that the pressure may be varied during the life of a charge of carbide at the will of the operator.

Another object is to provide such a generator 15 with means whereby the pressure to which the generator has been adjusted will be maintained substantially uniform throughout the life of a charge of carbide or until the pressure is manually varied.

Other aims, objects, and novel features, will be apparent from the following description and the accompanying illustrations, in which:

Fig. 1 is a vertical section of my improved generator showing the mechanism for both manually and automatically controlling the pressure of the gas generated therein;

Fig. 2 is a side view of my complete generator showing the mechanism on the outside of the 30 tank;

Fig. 3 is a horizontal section along the line 3—3 of Fig. 1 showing the construction of the carbide holder and its support; and,

Fig. 4 is a side view of the top of the generator showing the position of the interference rods.

My invention pertains especially to acetylene generators of the ebb-and-flow, water-feed type, having a closed tank and a chamber with an open bottom within the tank. Both the tank and chamber are partially filled with water leaving an air space in the tank and a gas space in the chamber above the water which seals the space between the tank and chamber. Carbide is carried in a suitable container within the chamber. As gas is generated in the chamber the increase in gas pressure lowers the water level in the chamber and raises the water level in the tank thereby compressing the air above it. As the gas is used 50 from the chamber water flows from the tank back in the chamber until it rises to a point where it comes in contact with the carbide when more gas is generated.

Generators of this general type originally had 55 the top of the tank open so the water therein was

exposed to the atmosphere. This form of generator has been very successful, but when the top of the tank was closed to increase the pressure of the generator trouble was encountered in starting the generator and in controlling the pressure of the generated gas. One method of overcoming this difficulty was to fill the freshly charged generator with water up to a particular point and then pump air into the top of the tank until sufficient water was forced up into the chamber in contact with the carbide to generate the desired gas pressure. This method of starting the generator was unsatisfactory unless it was located where a supply of compressed air was available, and, even then, the gas pressure varied considerably during the life of a charge of carbide.

The preferred form of my improved device by means of which these difficulties are overcome is shown in the accompanying drawing and it comprises a generator which consists essentially of a tank having an outer sheet steel shell 1 and an inner gas generating chamber 2 which makes a gas tight joint with the outer shell at 3. The outer shell is provided with a steel bottom 4, an agitator assembly 5, a water overflow valve 6, and a residue valve 7. The gas generating chamber 2 is provided with a gas deflector sheet 8 and a gas outlet pipe 9 which passes to the outside of the generator through gas tight openings 10 and 11 in the walls of the chamber and tank, respectively.

A removable top casting 12 is bolted to an angle iron ring 13 which is welded to the outer shell 1 of the generator. A rubber gasket 14 is provided to make a gas tight joint. An opening 15 is provided in the top casting 12 for filling the generator with water and for charging the generator with carbide. A charging door 16 is clamped over the opening 15 by means of a hinged cross bar 17, an eyebolt 18, and a handwheel 19. The joint between the door 16 and the top casting 12 is made gas tight by the use of a rubber ring gasket 20.

Carbide, preferably in the form of disintegrable molded carbide cakes 21, is contained in holders 22. The holders are provided with open wire bottoms 23 to permit the residue to sift through the openings therein as the carbide becomes exhausted. Covers 24 are also provided for the holders 22 to prevent moisture that is condensed on the top casting or charging door from dripping on the charge of carbide in the holders. The carbide holders are inserted into the generator through the opening 15 into a rotatable carrier ring 25 which is supported at its hub 26 by a

helical spring 63 that rests on a support or nut 26 which is threaded upon a vertical shaft 27 suspended from a bearing plate 28 by a washer 29 and a nut 30.

5 Extensible means for holding the nut 26 against rotation comprises a restraining sleeve 31 fixed to the nut 26 and extending downward around the shaft 27, and terminates some distance below the lower end of the shaft. A cap 32 is fixed 10 to the lower end of the restraining sleeve 31 and provided with a square hole at the axis thereof which loosely engages a square guide bar 33. This guide bar is supported on a horizontal cross member 34 which is welded to the sides of the 15 generating chamber 2 at 35. A guide sleeve 36 fixed to the nut 26 extends upward around the shaft 27 and inside the helical spring 63 and hub 25 of the carrier ring 24. Excessive upward movement of the carrier ring 24 is arrested by a collar 20 31 which is fixed to the upper end of the guide sleeve 36 above the carrier ring 24.

The vertical shaft 27, which is axially movable, is rotated in the nut 26 by a handwheel 38 mounted on the outer end of a spindle 39. This spindle 25 passes through a stuffing box 40 disposed in an opening near the top of the outer steel shell 1 of the tank. The driving mechanism includes a pair of cooperating helical gears, one of which is pinned to the spindle 39, and the other of which is indicated at 41 and pinned to the vertical shaft 27. The square guide bar 33 holds the nut 26 against rotation so that a vertical movement may be imparted to the nut 26 when the shaft 27 is rotated. Therefore, the charge of carbide may be 30 moved either up or down, with respect to the chamber 2 and the shaft 27, by turning the handwheel 38 in the proper direction so as to move the nut 26 and carrier 24 vertically along the shaft 27.

40 On the outside of the generator the gas outlet pipe 9 is connected to a hydraulic flash back 45 arrester 44 through a pipe 42 and swing check valve 43. In order to use the gas from the generator proper, a hose or outlet pipe may be connected to the outlet 45 of the flash back arrester 44. The generator is fitted with the usual 50 generating chamber relief valve 46 and hydraulic flash back arrester relief valve 47. Provision is made for automatically filling the hydraulic flash back arrester 44 with water through a valve 48 and pipe 49 which is connected at 50 to the tank 1. The water valve 48 is opened simultaneously 55 with the water overflow valve 6 by the operation of a filling lever 51. In order to insure the relief valves 46 and 47 being opened before the generator is otherwise opened, an interference rod 52, which extends vertically through openings in brackets 52' and 52'' secured to the wall of outer shell 1, is provided. A quadrant plate 60 53 made integral with the filling lever 51 is arranged to prevent the water valves 6 and 48 from being opened unless the relief valves 46 and 47 are open. An additional interference member 54, extending above the interference rod 52 and controlled by rotation of the feed spindle 39, is arranged to prevent the relief valves 46 and 47 from being manually opened unless the carbide containers 21 are raised to the upper 65 limit of their range of travel above the water level inside the generator. The interference member 54 is rigidly fastened to a horizontal interference rod 55 which is arranged to extend through an opening in a lug 56 integral and extending upwardly from the cover 12. Beyond the lug 56, the rod 55 extends through an opening 70

75 in a plate 57', which is made integral with a charging door interference handle 57. This handle is pivotally mounted on the cover 12, and when the rod 55 is in the position shown in Fig. 4, the handle 57 is in a locked vertical position 5 in the same vertical plane with the handwheel 19. By this construction, the charging door 16 cannot be opened while the rod 55 is in an interfering position, so that the operation of the generator cannot be interfered with while a charge 10 of carbide is positioned within the generating chamber to generate gas. A pressure gauge 58 is provided to indicate the pressure of the gas within the generator.

In the operation of charging, the generator 15 water is introduced through the opening 15 at the top of the generator until it overflows through the open valve 6, the hydraulic flash back arrester 44 being simultaneously filled to the level of the plug 59 in the side thereof. The carbide 20 containers are filled with disintegrable molded carbide cakes which are inserted through the top of the generator into the carrier or holder ring 24 and then the generator is closed.

25 Acetylene is generated by manually turning the hand wheel 38, thereby lowering the carbide charge to the level of the water in the generator. As the carbide is immersed in the water, generation of acetylene takes place, and the accumulation of gas in the generating chamber 2 30 lowers the water level therein and raises it in the outer tank 1, thereby compressing the gas in the compression chamber 62 above the water in the tank. The operating pressure of the generator is thus dependent upon the position of the charge of carbide in the generating chamber or bell 2, and this position may be manually 35 varied and controlled by means of the external pressure control hand wheel 38. The essential 40 parts of the generator are proportioned so as to make it impossible to generate gas at a pressure greater than 15 lbs. per square inch, which is the maximum permitted by the Underwriters' Laboratories for medium pressure portable automatic acetylene generators. 45

50 In some forms of the generator the spring 63 may be dispensed with and the carbide carrier 24 supported directly by the nut 26. In the operation of this generator it has been found, however, that the effect of rise in temperature due to the action of water on the carbide and rise in water level due to the accumulation of residue in the water in the generator, results in a gradual pressure rise throughout the life of a charge 55 of carbide. When spring 63 is used, however, this objectionable rise in pressure is overcome as the height of the carbide carrier is varied automatically according to the amount or weight of the carbide. With a fresh charge of carbide in the generator, the spring 63 is compressed so that the carbide carrier, with the charge of carbide therein, occupies a lower position with respect to the bell than when the charge of carbide is exhausted. As the charge becomes exhausted its 60 weight becomes less, thereby exerting less pressure on the spring, which is consequently compressed to a lesser degree so that the carbide holder with the charge of carbide therein gradually rises with respect to the chamber during 65 the life of the charge of carbide. In the particular generator shown and described herein the carbide holders, when fully charged, ride at a level about 2 inches lower than they do when empty. In other words, for a given setting of 70 75

the pressure control hand wheel 38, the expansion of the spring 63 causes the carbide containers 21 to gradually move upward as the carbide is consumed and sifts through the bottom of the 5 containers so as to automatically maintain a substantially constant and uniform pressure within the generator throughout the life of a charge of carbide.

While I have shown and described a particular embodiment of my invention, it will be obvious to those skilled in the art that modifications may be made without departing from my invention and I, therefore, aim in the appended claims to cover all such modifications as fall 15 within the true spirit and scope of my invention.

I claim:

1. The combination with an acetylene generator having a closed tank and a generating chamber within said tank; of means including a movable element for supporting a charge of carbide within said chamber; automatic means coacting with said movable element for varying the position of the charge of carbide within said chamber; and a single means capable of vertically 20 bodily moving said movable element and said automatic means coacting therewith.

2. The combination with an acetylene generator having a closed tank and a generating chamber within said tank; of means including a movable element for supporting a charge of carbide within said chamber; automatic means coacting with said movable element and controlled by the variations in weight of said charge of carbide for varying the position thereof within said chamber; and a single means operable from the outside of said chamber for vertically bodily moving said movable element and said automatic means coacting therewith.

3. In an acetylene generator having a tank 40 adapted to contain water and a generating chamber within said tank; a vertical shaft at the axis of said chamber; a plurality of removable carbide holders at the surface of said water supported by said shaft and rotatable therearound; means for partially immersing said holders in said water; said generator having an eccentric opening in the top thereof through which said carbide holders may be inserted and removed; and a removable cover for said opening.

50 4. In an acetylene generator having a closed tank adapted to contain water and a generating chamber within said tank; a cover closing the top of said chamber; a vertical shaft supported by said cover at the axis of said chamber; a hub supported by said shaft and rotatable thereon; a plurality of partially submersible carbide holders carried by said hub and symmetrically arranged around said shaft; means for partially submerging said holders; said cover having an eccentric opening therein through which said carbide holders may be inserted and removed; and a removable cover for said opening.

5. The combination in an acetylene generator having a tank and a generating chamber within said tank; of a support within said chamber; resilient means resting upon said support; a carrier resting upon said resilient means, one or more carbide holders supported by said carrier and movable therewith with respect to said support by a variation in the weight of the carbide in said holder and a single means for varying the position of said support and said resilient means with respect to said chamber from the outside of said generator.

75 6. An acetylene generator comprising a gen-

erating chamber; a single vertical shaft supported within said chamber and rotatable from the outside of said generator; a support on said shaft and axially movable thereon when the shaft is rotated; resilient means disposed about said shaft above said support and carried thereby; a vertically movable carrier on said shaft above said resilient means and carried thereby; and one or more carbide holders supported by said carrier.

7. An acetylene generator comprising a chamber having a gas outlet and adapted to contain water; said chamber having a cover provided with an opening; a plurality of carbide holders within said chamber, each having openings to admit water to the carbide carried thereby; a support for said holders comprising means for partially immersing said holders in said water; and means whereby any one of said holders may be adjusted to register with said opening in the cover.

8. In an acetylene generator having a tank adapted to contain water and a generating chamber in said tank; a plurality of removable carbide holders supported in said generating chamber and provided with respective openings to simultaneously expose the carbide therein to contact with said water; means for simultaneously moving said holders into contact with said water; and said chamber having an eccentric opening in the top through which said holders may be successively inserted and removed.

9. An acetylene generator comprising a generating chamber; an axially immovable vertical shaft supported within said chamber; means for carrying a charge of carbide, means for supporting said carbide-carrying means on said shaft; resilient means coacting with said carbide supporting means for automatically varying the vertical position of said carbide-carrying means; and a single means operable to bodily raise and lower said carbide-carrying means and said resilient means along said shaft.

10. An acetylene generator comprising a casing having a removable cover to provide an enclosed generating chamber; means for carrying a charge of carbide; means including said casing for supporting said carbide-carrying means within said chamber; a single means operable from the outside of said generator for moving said carbide-carrying means vertically within said chamber to control the pressure of the gas generated therein; and resilient means coacting with said carbide supporting means to maintain the pressure of the generated gas substantially constant as the charge of carbide is being consumed; said last-mentioned means being vertically movable simultaneously with said carbide-carrying means.

11. An acetylene generator comprising a chamber having a gas outlet and adapted to contain water; said chamber having a cover provided with an opening; a plurality of carbide holders adjustably supported within said chamber and having openings to admit water therein to contact the carbide carried thereby; and means whereby any one of said holders may be adjusted to register with said opening in the cover.

12. An acetylene generator comprising a chamber having a gas outlet and adapted to contain water; said chamber having a cover provided with a charging opening; a plurality of carbide holders adjustably supported within said chamber and adapted to be removed therefrom through

- said opening; such holders having openings to admit water therein to contact the carbide carried thereby; and means whereby said holders are severally adjustable to register with said opening in the cover.
13. In an acetylene generator comprising a generating chamber and a compression chamber; a quantity of water in said generator partially filling said chambers and forming a liquid seal therebetween; one or more carbide holders vertically movable in said generating chamber; a single means operable from the outside of said generator for manually lowering said carbide holder into said water to generate acetylene in said generating chamber thereby, forcing some of said water into said compression chamber to compress the gas therein and create an initial pressure in said generator; and movable means supporting said carbide holder and being lowered by said manually operable means; said last-mentioned means being automatically operable to raise said carbide holder as the water level in the generator is raised by the accumulation of carbide residue therein so as to maintain a substantially uniform pressure in the generator throughout the life of a charge of carbide.
14. The combination with an acetylene generator having a tank and a generating chamber within said tank; of means for supporting a charge of carbide within said chamber; means manually operable from the outside of said generator for varying the height of said carbide supporting means with respect to said chamber; and automatic means controlled by the variation in weight of said charge of carbide for varying the height of said carbide supporting means with respect to said chamber.
15. The combination with an acetylene generator having a tank and a generating chamber within said tank; of means for supporting a charge of carbide within said chamber; automatic means controlled by the variation in weight of said charge of carbide for varying the height of said carbide supporting means with respect to said chamber; and means manually operable from the outside of said generator for varying the height of both said automatic means and said carbide supporting means with respect to said chamber.
16. In an acetylene generator having a tank and a generating chamber within said tank; a rotatable shaft supported in a vertical position within said chamber; a nut threaded upon said shaft; a carbide holder supported by said nut; means for holding said nut against rotation; and means for manually rotating said shaft from the outside of said generator.
17. In an acetylene generator having a tank and a generating chamber within said tank; a rotatable shaft supported in a vertical position within said chamber; a nut threaded upon said shaft; a carbide holder supported by said nut; a sleeve attached to said nut; a cap having a square opening therein carried by said sleeve; a square guide bar supported in fixed position within said chamber and projecting through said opening; a carbide holder supported by said nut; and means for rotating said shaft from the outside of said generator.
18. In an acetylene generator having a tank and a generating chamber within said tank; a rotatable shaft supported in a vertical position within said chamber; a nut threaded upon said shaft; a carbide holder supported by said nut; means for holding said nut against rotation; a driven gear fixed to said shaft; a driving gear meshed with said driven gear; a spindle fixed to said driving gear and extending outside of said generator; means for providing a gas tight joint between said spindle and the wall of said generator; and a handle fixed to said spindle by means of which it may be rotated.
19. In an acetylene generator having a tank and a generating chamber within said tank; a rotatable shaft supported in a vertical position within said chamber; a nut threaded upon said shaft; a carbide holder supported by said nut; means between said carbide holder and said nut for automatically varying the height of said carbide holder with respect to said nut according to the amount of carbide in said carbide holder; means for holding said nut against rotation; and means for manually rotating said shaft.
20. In an acetylene generator having a tank and a generating chamber within said tank; a rotatable shaft supported in a vertical position within said chamber; a nut threaded upon said shaft; a carbide holder supported by said nut; a spring between said nut and said carbide holder; means for holding said nut against rotation; and means for manually rotating said shaft.
21. In an ebb-and-flow, water-feed, acetylene generator having a tank and a generating chamber within said tank; a rotatable shaft supported by a wall of said chamber in a fixed vertical position therein; a nut threaded upon said shaft; a carbide holder loosely mounted upon said shaft above said nut; a compressible spring surrounding said shaft between said nut and said carbide holder; extensible means for holding said nut against rotation having a portion thereof attached to a wall of said chamber; and means for rotating said shaft having a portion thereof extending outside said generator for manual operation.
22. In an ebb-and-flow, water-feed, acetylene generator having a tank and a generating chamber within said tank; a vertical shaft within said chamber and carried thereby; a nut threaded upon said shaft; a restraining sleeve fixed to said nut and extending downward therefrom around said shaft and below the lower end thereof; a cap having a square axial opening therein fixed to the lower end of said sleeve below the lower end of said shaft; a square guide bar carried by said chamber in axial alignment with said shaft and extending loosely through the square opening in said cap; a guiding sleeve fixed to said nut and extending upward therefrom around said shaft; a compressible helical spring surrounding said guiding sleeve and resting on said nut; a carbide holder slidably mounted on said guiding sleeve and resting on said helical spring; a collar fixed to the upper end of said guiding sleeve above said carbide holder in loose engagement with said shaft; and means for manually rotating said shaft from the outside of said generator.

MAURICE P. DE MOTTE.
